CONVEYER

Filed May 17, 1929

UNITED STATES PATENT OFFICE

EARL F. OYSTER, OF SHAKER HEIGHTS, OHIO, ASSIGNOR TO THE OSBORN MANUFACTURING COMPANY, OF CLEVELAND, OHIO, A CORPORATION OF OHIO

CONVEYER

Application filed May 17, 1929. Serial No. 363,909.

The present invention relates to a method of and apparatus for distributing sand or other fluent material to a plurality of stations. More particularly, the invention relates to a 5 flight conveyer especially adapted for use in connection with a system including molding machines, a storage chamber for sand, hoppers for supplying sand to the molding machines, and means for conveying the sand 10 from the storage chamber to the hoppers; and the primary object of the invention is to provide means for preventing waste of sand. Further objects will appear as the description proceeds. To the accomplishment of the 15 foregoing and related ends, said invention, then, consists of the means hereinafter fully described and particularly pointed out in the claims.

The annexed drawing and the following 20 description set forth in detail certain mechanism embodying the invention, such disclosed means constituting, however, but one of various mechanical forms in which the principle of the invention may be used.

25 In said annexed drawing:

Fig. 1 is a more or less diagrammatic view of an installation of the character described; Fig. 2 is an enlarged elevation of a section of a flight conveyer; Fig. 3 is a view taken substantially in the plane of the line 3—3 in Fig. 1 and on a still further enlarged scale of one of the flights and its associated parts; and Fig. 4 is a diagrammatic view taken substantially in the plane of the line 4—4 in Fig. 1.

35 In installations of the general type to which reference has been made, it is usual to provide an elevator fed from a storage chamber, said elevator being adapted to raise the sand and deposit the same in one end of a 40 trough. The trough is disposed above the open ends of a plurality of hoppers, and is formed with ports in its bottom registering with said open hopper ends. An endless chain or belt is provided, one run thereof being located adjacent the trough, and said chain or belt carries flights, or pusher plates which extend downwardly from said chain or belt to enter the trough. As the endless member is advanced, the plates push the sand 45 along the trough, whereby some of the sand is

caused to drop through the ports and into the hoppers below. It is, of course, necessary to supply an excess of sand to the trough in order to insure filling of the final hopper, and ordinarily this excess sand is pushed off the end of the trough and is allowed to build up in a pile which must later be returned to the storage chamber in wheel barrows, or by some other means. It is an object of the present invention to eliminate the necessity for this manual return of sand.

Referring more particularly to the drawings, it will be seen that the installation includes a series of hoppers 10 adapted to be fed from a storage chamber 11. A conveyer 12 is arranged to carry sand in stated quantities from said chamber to a container 13 whence the sand flows into the elevator 14, being discharged therefrom through a spout 15 into an end of a trough 16. Immediately 55 below the trough 16 and in the same vertical plane therewith there is mounted a second, substantially duplicate, trough 17, one end 18 of which extends beyond the corresponding end 19 of the trough 16. In line with the troughs 16 and 17 there are mounted a pair of sprockets 20 over which extends a conveyer 60 65 70 75 80 85 90 95 100

As will be clear from Fig. 1, the upper run 21 of the conveyer is positioned adjacent the trough 16 while the lower run 22 thereof is positioned adjacent the trough 17. This conveyer comprises a pair of endless chains built up of links 23 pivoted to each other and carrying rollers 24. Said rollers 24 are adapted to run in trackways 25 mounted on the upper edges of the troughs 16 and 17. Contrary to usual practice, the flights 26 carried by this conveyer are provided not only with downwardly extending portions 27 adapted to scrape through the trough 16, but also with upwardly extending portions 28 adapted, when in the lower run 22, to scrape through the trough 17. As will be clear from the drawings, the flights 26 extend substantially equal distances in opposite directions from the conveyer in a plane perpendicular to the plane of travel of said conveyer.

As in usual practice, the trough 16 is provided with ports 31 in its bottom aligned with

the open upper ends of the hoppers 10. The trough 17 is likewise provided with ports 32 in its bottom, such ports being vertically aligned with the corresponding ports in the trough 16 and with the hoppers 10. In operation, then, sand is delivered from the spout 15 of the elevator 14 into the end 29 of the trough 16, such sand being delivered in quantities in excess of the needs of the hoppers 10. As the conveyer is advanced, the lower portions 27 of the flights 26 pick up the sand delivered from the spout 15 and carry it along through the trough 16. As the sand passes the ports 31 in the bottom of the trough, some sand will fall through each of the apertures and into the hoppers 10. As has been indicated, however, an excess of sand must be provided and, in accordance with the present invention, this excess is brushed off the end 19 of the trough 16 and falls into the end 18 of the trough 17. Following a particular flight 26, from the point where it moves beyond the end 19 of the trough 16, it will be seen that this flight is carried around the sprocket 20 and then starts back, moving toward the left as viewed in Fig. 1. It will be seen that, at this time, the portion 28 of this flight points downwardly, and it is the portion 28 which enters the trough 17. Here the flight 26 comes in contact with sand discharged into the trough 17 from the trough 16, and such sand is pushed toward the left as viewed in Fig. 1 by the ends 28 of the flights 26. As the sand is moved in this direction through the trough 17, another opportunity is provided for supplying sand to the hoppers 10, it being understood that sand will fall through the ports 32 of the trough 17 into any hopper which is not completely filled.

If sand is carried into the trough 17 in such large quantities that not all of it can be received in the hoppers 10, any excess sand will be carried completely through the trough 17 and discharged from the end 30 thereof, falling thus into the storage chamber 11.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In an organization of the class described, the combination of a plurality of hoppers having open upper ends, a trough mounted above said hoppers, said trough being provided with ports in its bottom vertically aligned with said open ends, a second trough mounted above said first trough and in the same vertical plane therewith, said second trough being provided with ports vertically aligned with said open hopper ends and with the ports in said first trough, an endless flex-

ible member having its lower run disposed adjacent said first trough and its upper run disposed adjacent said second trough, and means carried by said member and adapted to enter said troughs successively.

2. In an organization of the class described, the combination of a plurality of hoppers having open upper ends, a trough mounted above said hoppers, said trough being provided with ports in its bottom vertically aligned with said open ends, a second trough mounted above said first trough and in the same vertical plane therewith, said second trough being provided with ports vertically aligned with said open hopper ends and with the ports in said first trough, an end of said first trough extending beyond the corresponding end of said second trough, an endless flexible member having its lower run disposed adjacent said first trough and its upper run disposed adjacent said second trough, and means carried by said member and adapted to enter said troughs successively.

3. In an organization of the class described, the combination of a plurality of hoppers having open upper ends, a trough mounted above said hoppers, said trough being provided with ports in its bottom vertically aligned with said open ends, a second trough mounted above said first trough and in the same vertical plane therewith, said second trough being provided with ports vertically aligned with said open hopper ends and with the ports in said first trough, an end of said first trough extending beyond the corresponding end of said second trough, means for depositing fluent material in the opposite end of said second trough, an endless flexible member having its lower run disposed adjacent said first trough and its upper run disposed adjacent said second trough, and means carried by said member and adapted to enter said second and first troughs successively.

4. In an organization of the class described, the combination of a plurality of hoppers having open upper ends, a trough mounted above said hoppers, said trough being provided with ports in its bottom vertically aligned with said open ends, a second trough mounted above said first trough and in the same vertical plane therewith, said second trough being provided with ports vertically aligned with said open hopper ends and with the ports in said first trough, an end of said first trough extending beyond the corresponding end of said second trough, a storage chamber for fluent material, means for delivering material from said chamber to the opposite end of said second trough, an endless flexible member having its lower run disposed adjacent said first trough and its upper run disposed adjacent said second trough, and means carried by said member and adapted to enter said second and first troughs successively, whereby, when said member is driven, any ex-

cess material delivered to said second trough is caused to fall from said first-mentioned end of said second trough into the corresponding end of said first trough, and the opposite end of said first trough being disposed immediately above said storage chamber whereby excess material delivered to said first trough is discharged into said chamber.

Signed by me this 15th day of February,
10 1929.

EARL F. OYSTER.
